UNITED STATES PATENT OFFICE.

ISAAC P. TURNER, OF TROY, NEW YORK, ASSIGNOR TO A. CLARK FELLOWS
OF SAME PLACE.

CUFF.

SPECIFICATION forming part of Letters Patent No. 252,277, dated January 10, 1882.

Application filed August 12, 1881. (No model.)

To all whom it may concern:

Be it known that I, ISAAC P. TURNER, a citizen of the United States, residing at Troy, in the county of Rensselaer and State of New York, have invented new and useful Improvements in Cuffs, of which the following is a specification.

This invention relates to that class of ladies' or gentlemen's wear known as "false" or "detachable" cuffs.

In the ordinary way of making these cuffs the fabric is cut in the desired shape, and of as many thicknesses as required, one of such thicknesses or pieces forming the face, one the facing, and the remaining piece or pieces the interlining. These pieces are placed together with the face and the facing pieces wrong side out, and run or coarsely stitched together around three of the edges, and then turned 20 right side out through the open or unstitched edge, which is usually designated as the "closing edge." This closing edge is then folded inward and stitched, which operation closes the cuff; but in cuffs thus made great care 25 must be exercised in turning in the closing edge of the cuff and skilled workmen employed to perform the operation, otherwise there will be a slack or fullness in the facing after the cuff has been turned and finished, 30 whereby the fabric will invariably wrinkle in laundrying. Again, a cuff has been made of several thicknesses of woven fabric, of which the back or front of the cuff is formed of one piece and thickness, having therein a plait in 35 which is formed a slit. The cuff after being run all round is turned right side out through this slit, and the plait afterward stitched to the other thickness or thicknesses of the cuff. This cuff, however, presents some disadvantages in its manufacture, since in turning the 40 plait will usually loose its line of fold, and hence refolding is required. There will also be a line of fold outside of the cuff, which, when stitching the plait after turning, will not be 45 stitched down, it not being practicable to run the line of stitching too near the edge of the fold.

It will be seen hereinafter that in the manufacture of cuffs according to my invention the 50 crease and seam are completed before turning,

whereby the crease will be turned in, leaving the line of seam alone visible, thus giving a plane facing to the cuff.

With a view of obviating such defect detachable cuffs have been made with a front or 55 face formed of one piece of fabric and a back of two separate pieces, each folded in the middle, and with this double back stitched to the front along all the outer edges with or without a thickness of interlining, and the cuff 60 then turned right side out through the long open space between the two lapped folded edges of the two pieces of the back, and the turned cuff afterward closed by stitching the lapped parts of the two pieces of the double 65 back to the other thickness or thicknesses of the cuff; but in a cuff of such construction the stitches pass through the front or face of the cuff, as well as through its back along the lapping edges of the two parts of the latter, so 70 that there will be one or more rows of stitches along the face of the cuff; also, a cuff so constructed cannot be made with only two thicknesses of fabric, and must necessarily be made of at least three thicknesses, and the inner 75 thicknesses of the double back, which serves as an interlining, is necessarily of the same fine, thin, and expensive fabric that constitutes the outer surface of the back, whereas a much thicker, stiffer, and cheaper fabric is 80 generally desirable for the interlining of cuffs. In another instance the thicknesses of the cuff have been cut of different sizes and run, and then held up while stitching, which operation involves skill and care, and, moreover, a thick- 85 ness is sometimes left unstitched.

It is the object of the present invention to take up such slack or fullness of the cuff in an entirely novel manner, and to such end I form a crease or creases and a seam or seams along 90 the facing before the cuff is turned, whereby sufficient material will be taken up to take up all fullness after the cuff has been turned, as hereinafter described and illustrated in the accompanying drawings, in which—

Figure 1 represents the facing side of a finished cuff made in accordance with my invention. Fig. 2 is an enlarged transverse section taken through the same before it is laundried. Fig. 3 illustrates the cuff after it has been run

and before it has been turned, the face and facing in this instance being spread apart so as to form the seam along the center of the facing.

Fig. 4 represents a finished cuff with rounded end edges and having a slightly-modified construction of ends. Fig. 5 represents the same after it is run and before it is turned; and Fig. 6 represents a "run" cuff before it is turned, formed with two creases and seams.

- 10 In the drawings, A indicates the face; B, the facing, which is usually of muslin or other suitable light fabric; and C C, the intermediate pieces, which constitute the interlinings of the cuff. These pieces are all cut of equal width, 15 and, being superposed with the face and the facing-pieces wrong side out, are run or coarsely stitched along their longer or side edges, so as to leave an opening at each end of the cuff, in order that it may be turned right side out 20 through either one of these openings. Preparatory to thus turning the cuff, however, I form a crease and seam in the facing-piece B of the cuff along a line which is at or about midway of its longer or side edges, the said 25 crease and seam being made by spreading apart the face and facing-pieces of the cuff, as shown in Fig. 3, and forming a crease, D, along or about along the center of the facing-piece, and then running a line of stitching, d, a little back 30 of the crease, so as to form the seam d'. After this crease and seam have been thus formed and stitched and the cuff turned right side out through either one of its end openings, it will be found that the crease and seam have taken 35 up sufficient of the material of the facing of the cuff to take up all of the slack or fullness which would otherwise occur.

After the cuff has been turned right side out it is turned in at its ends and stitched, as usual, 40 so as to form corded edges along its sides and gutter-seams along its ends. If, however, it is desired to avoid these gutter-seams at the ends of the cuff, and especially in cuffs having rounded ends, where it is more desirable to 45 have the end edges present the appearance of the side edges, so that a uniform finish will be obtained along the entire edge of the cuff, the openings at the ends of the cuff can be somewhat enlarged by notching in the facing B, as 50 shown at E, Figs. 4 and 5, pointed pieces F, cut out somewhat larger than these openings, being run along their outer edge with the cuff, so that after turning the latter right side out 55 these pieces can be brought over to cover the openings, and their diverging edges being inserted under the ends of the facing, and the whole then stitched through, as shown in Fig. 4, whereby the end edges of the cuff will present the same finish as its side edges, and the 60 line of stitching necessary to secure the pieces

F will simply give an ornamental appearance at the ends of the cuff without detracting from its value.

The depth of the crease or the distance of the seam from the line of the crease will, of course, be determined by the amount of slack or fullness to be taken up; and, if desired, instead of a central crease, as just described, two or more of these creases and seams can be formed nearer the edges of the cuff, as shown in Fig. 6.

Cuffs thus made can be laundered smooth and even without difficulty, and will have none of the slack or fullness pertaining to many of the cuffs now made.

The defects incident to the manufacture of cuffs, as heretofore made, with a view to obviating the slack or fullness, as stated in the preamble, are also completely avoided, and the seam d' shown in Figs. 1 and 4 will only appear on the facing B, which, when the cuff is worn, constitutes the inner side of the same, since the crease and seam are formed before the cuff is turned, and hence after it is turned the crease will be on the inner side of the facing and the seam on the outer side thereof.

Having thus described my invention, what I claim is—

1. The method herein described of taking up the slack or fullness in a false or detachable cuff, the same consisting in forming a crease and a seam in the facing between its side edges after the thicknesses composing the cuff have been run together and before turning the same, substantially as described.

2. The method of taking up the slack or fullness in the back facing of a detachable cuff, the same consisting in cutting the parts of equal widths, running or stitching them together at the edges of the said parts after they are laid together wrong side out, then forming a crease along the facing-piece between its edges and running a seam along the said crease, and finally turning the cuff right side out through an opening at either of its ends, substantially as described.

3. As a new article of manufacture, a detachable cuff formed with a crease or creases and a seam or seams along its facing between the side edges of the latter, whereby the fullness or slack of the facing is taken up, and when turned the seam alone will be visible, substantially as described.

In testimony whereof I have hereunto set my hand in the presence of two subscribing witnesses.
